UNITED STATES PATENT OFFICE.

MOSES MOSLER, OF CINCINNATI, AND CARL BARTELS, OF HAMILTON, OHIO, ASSIGNEES
TO THE MOSLER SAFE COMPANY, OF NEW YORK, N. Y.

SAFE CONSTRUCTION.

1,153,329.

Specification. Letters Patent. Patented Sept. 14, 1915.

Application filed February 9, 1915. Serial No. 7,124.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Safe Construction, of which the following is a specification.

10 This invention pertaining to improvements in safe-construction will be readily understood from the following description taken in connection with the accompanying drawings in which:—

15 Figure 1 is a front elevation of a safe-body exemplifying our invention: Fig. 2 a rear elevation of the same: Fig. 3 a rear elevation of the body with the back-plate absent: Fig. 4 a front elevation of the back-plate: Fig. 5 a horizontal section in the plane of line *a* of Figs. 1, 2, 3 and 4: Fig. 6 a horizontal section, at one rear corner of the safe, in the plane of line *a* of Figs. 1, 2, 3 and 4 illustrating the structure in incomplete 25 form: Fig. 7 a similar view illustrating the structure in complete form: and Fig. 8 a horizontal section in the plane of line *a* of Figs. 1, 2, 3 and 4 of the safe-body with the door shown in plan.

30 A diversity of scales is employed in the drawings.

In the drawings:—1, indicates the body of the safe, whose exterior form is immaterial, one feature of our invention requiring the 35 safe-body or one of its walls to be formed of material possessing a certain degree of malleability: 2, the door opening therein, illustrated as being of circular form and provided with interiorly projecting locking 40 lugs: 3, a circular opening extending through one of the walls of the safe-body, this opening being shown in the illustration as being in the rear wall of the body: 4, a circular plate separably inserted in the opening 45 3 and having its perimeter tapering with an outward convergence: 5, lugs carried by the safe-body and projecting inwardly past the margin of opening 3: 6, hooks carried by plate 4 and adapted, as the plate is being 50 put in place in the opening in the body, to pass between the body-lugs and then, by rotation of the plate, to pass in behind the lugs: 7, an inner safe disposed within the

outer one and of a size adapting it to pass through the rear opening when the plate 55 therein is absent: 8, the door-opening in the front of the inner safe, the same being in axial alinement with the door-opening in safe-body 1, this door-opening of the inner safe, being illustrated as being interiorly threaded: 9, an accurately fitted rabbeted joint between the front of the inner safe and the rear portion of the margin of door-opening 2: 10, the space surrounding the inner safe between it and the outer safe-body: 11, 60 a filling of plastic material, as cement, occupying this space; and 12 a door closing the door-openings in both the inner and outer safes.

Considering only the outer safe-member, 70 it or that wall of it which contains the circular opening 3 is to be of malleable material. Our best contemplation at present is that the safe-body 1 and its plate 4 be formed of manganese steel castings, this metal being uncuttable but malleable to a satisfactory extent. In constructing the outer safe-member the margin of the circular opening 8 will be cylindrical, while the margin of plate 4 will be frusto-conical, both as indicated in Fig. 6. The plate may thus be freely entered into the opening in the safe wall, and, after this has been done, the margin of the opening may be swaged inwardly 80 to tightly engage and overhang the margin of the plate, as indicated in Figs. 5 and 7. The plate is thus securely locked in place and cannot be released by any cutting operation. We have illustrated the opening at the plate as being in the rear wall of the 90 safe, and this will be the most desirable location under most all conditions. The forming of the safe-body with the large opening for the inserted plate provides special facilities, not only for the insertion of an 95 inner safe larger than the door-opening in the outer safe-member, but also facilitates the production of the casting forming the outer safe-body, as the core producing the interior of the casting may have a plurality of large core-prints instead of depending upon the single one at the door-opening.

The inner and outer safes having been accurately fitted together at their joint 9, the 105 outer safe-body is set front downward and

the inner safe positioned within it. After this the filling is poured, and, while the filling is still plastic, the plate is inserted and adjusted angularly till its hooks engage under the lugs of the safe-body. Then, regardless of the swaging of the safe-body to the plate, the filling, when it hardens, will prevent such angular movement of the plate in its opening as to release it from the safe-body, a double protection being thus afforded.

Our best present contemplation is that the inner safe shall be formed of a manganese steel casting, and when the described structure has been produced there results an inner and outer safe-member with fireproof filling between them.

It is to be understood that, regardless of what may be the exterior form of either the inner or outer safe-member, the opening in the wall of the outer safe-member must be of sufficient size to permit the insertion through it of the inner safe-member. While the invention obviously lends itself to a variety of door-constructions, we give our preference to a circular door-opening common to both safe-members the front portion of the door-jamb being formed in the outer safe-member and the rear portion of the door-jamb being formed in the inner safe-member. We have seen fit to illustrate our invention in connection with a door-jamb provided with locking-lugs in its front portion and a screw in its rear portion, such a door-opening being adapted for the peculiar compound door of our United States Patent No. 1,118,436 of November 24th 1914.

We claim:—

1. Safe-construction comprising, a wall having an opening therethrough and formed of malleable material at the margin of the opening, a support projecting inwardly of said margin at the inner surface of said wall, a plate fitting said opening and having its perimeter tapering with an outward convergence, the margin of the opening being swaged inwardly into contact with the perimeter of the plate after the plate has been inserted in the opening, combined substantially as set forth.

2. Safe-construction comprising, a wall having through it a circular opening, a circumferential series of lugs projecting inwardly of the opening, a plate filling the opening and resting on said lugs, a circumferential series of hooks on the back of the plate and adapted to pass between said lugs and then to engage behind the lugs of the angular adjustment of the plate, plastic filling applied at the inner surface of the wall and plate engaging the hooks and lugs, and means inwardly of said plate and filling to prevent the displacement of said filling, combined substantially as set forth.

3. Safe-construction comprising, a wall

having through it a circular opening, a circumferential series of lugs projecting inwardly of the opening, a plate filling the opening, a circumferential series of hooks on the back of the plate and adapted to pass between said lugs and then to engage behind the lugs by the angular adjustment of the plate, plastic filling applied at the inner surface of the wall and plate and engaging the hooks and lugs, and means inwardly of said plate and filling to prevent displacement of the filling, the periphery of the plate contracting outwardly and the margin of the opening being swaged into contact with said periphery combined substantially as set forth.

4. Safe-construction comprising, an outer safe-member provided with a door-opening and with an opening in one of its other walls, an inner safe-member disposed within the outer safe-member and supported therein free therefrom at its back and around its exterior and adapted to pass through the last-mentioned opening, means for supporting the inner safe-member within the outer one, a plate secured in said last-mentioned opening, and a filling of plastic material disposed in the space between the outer and inner safe-members, said filling serving to position said inner safe-member relative to said plate, combined substantially as set forth.

5. Safe-construction comprising, an outer safe-member provided with a door-jamb and with a supplemental opening in one of its walls larger than said door-jamb, an inner safe-member provided with a door-jamb in axial alinement with the door-jamb of the outer safe-member, a joint being formed between the front of the inner safe-member around its door-jamb and the rear portion of the door-jamb of the outer safe-member, a plate applicable from the outside of the outer safe-member and permanently closing said supplemental opening, means for maintaining the inner safe-member in such relation to the outer safe-member that the two door-jams will be in direct contact, and a door hinged to the outer safe-member and adapted to move into and close both door-jams, combined substantially as set forth.

6. Safe-construction comprising, an outer safe-member provided with a door-jamb and with a supplemental opening in one of its walls larger than said door-jamb, an inner safe-member provided with a door-jamb in axial alinement with the door-jamb of the outer safe-member, a joint being formed between the front of the inner safe-member around its door-jamb and the rear portion of the door-jamb of the outer safe-member, a plate applicable from the outside of the outer safe-member and permanently closing said supplemental opening, a filling of plas-

tic material disposed in the space between the inner and outer safe-members and serving to position the two safe-members in such relation to each other that portions of the

5 two door-jambs will be in direct contact, and a door hinged to the outer safe-member and adapted to move into and close both

door-jambs, combined substantially as set forth.
